(No Model.)

H. T. CLAWSON.

ICE SHAVING MACHINE.

No. 391,452.

Patented Oct. 23, 1888.

Inventor:
Henry T. Clawson
by Chas. J. H. Dick,
his attorney.

UNITED STATES PATENT OFFICE.

HENRY T. CLAWSON, OF NEWARK, NEW JERSEY.

ICE-SHAVING MACHINE.

SPECIFICATION forming part of Letters Patent No. 391,452, dated October 23, 1888.

Application filed January 6, 1888. Serial No. 259,965. (No model.)

To all whom it may concern:

Be it known that I, HENRY T. CLAWSON, a citizen of the United States, residing at Newark, in the county of Essex and State of New Jersey, have invented certain new and useful Improvements in Ice-Shaving Machines, of which the following specification is a full, clear, and exact description.

This invention relates more particularly to machines for shaving ice by means of a cutter-head revolving in or at the end of a tubular ice-holder; but it may of course be applied to any machine for shaving ice or other purpose to which it is or may be adapted.

In ice-shaving machines of the above description it is important to have the knives or cutters extend outward (*i. e.*, radially, or nearly so) from the center of the cutter-head practically to the inner wall of the ice-holder, so that they may remove the ice from the whole face of a block in the ice-holder and not leave a core or other projection to arrest or interfere with the advance of such block.

The present invention consists in a new construction of cutter-head and in the combination of the same with an ice-holder, especially one in the form of a curved tube of about the same width or diameter as the cutter-head.

In the accompanying drawings, which form part of this specification, Figure I is a longitudinal vertical section of an ice-shaving machine provided with a cutter-head constructed in accordance with the invention; Fig. II, a face view of the cutter-head, and Fig. III a back view of the same.

The cutter-head is composed of a hub, A, with arms 1, and plates B, fastened to said arms, each of said plates being a sector of a circle, (a semi-circle, as shown,) and each having a lip, 2, which extends radially from the center of such circle, is bent outward from the body of the sector, and has its edge sharpened to form a knife. Such plates are secured to the hub A with the inner corner, 3, of the lips or knives 2 in the line of the axis of the hub, so that each knife-edge extends radially from the axis or center of the cutter-head and will remove the ice from a block without leaving a core. These plates are or may be stamped out and have screw-holes punched therein by suitable dies, and the lips 2 are bent out, tem-

pered, and sharpened. The plates are then ready to be fastened in place on the hub A by means of screws 5, tapped into the ends of the arms 1. The spaces 6 for the passage of the shaved ice being formed between the lips 2 and the adjacent edges of the adjoining plates, no slitting or slotting of the cutter-head is necessary.

The arms 1 are made to project forward in the direction of the axis of the cutter-head, so as to leave between them a hollow space, 6, in the front of the hub A, behind the plates B, into and through which space the shaved ice may freely pass. The cutter-head thus made is strong, light, effective, easily made, cheap, and with no parts to get out of order or to require adjustment by the user. The knives can be tempered very hard without danger of breaking. When the cutting-edges are worn off, the old plates can be removed and replaced with new ones by the user without any difficulty and at a very slight expense.

In the machine the new or improved cutter-head A B is preferably mounted on a horizontal shaft, C, and placed upright in the lower end of a tubular curved ice-holder, D, in which is placed the ice to be shaved, a follower, E, connected with a hand-lever, F, being employed to force the ice against the cutters.

The ice-holder has about the same width or diameter as the cutter-head, so that the knives act on both sides of the axis. On the opposite side of the cutter-head from the ice-holder is a shaved-ice chamber, G, containing a removable drawer, H, into which the shaved ice falls. The presence or absence of this chamber and drawer is not material to the invention.

I claim as my invention or discovery—

1. The cutter-head composed of a hub with forwardly-projecting arms and a number of separate flat plates, which are attached to said arms and lie in a common plane at right angles to the axis of said hub, each plate being in the form of a sector whose center of curvature coincides with the axis of said hub, and having along one of its radial edges a lip, which is bent outward and is sharpened to form a knife or cutter, and the said arms being separated from one another and having

their outer ends at a distance from the axis of said hub, so as to leave a clear space between the inner end of the hub and the said sector-shaped plates at the center of the cutter-head, 5 substantially as described.

2. The combination, with the ice-holder and the follower, of the cutter-head arranged at the end of said ice-holder, and composed of a hub with forwardly-projecting arms and a 10 number of separate flat plates, which are attached to said arms and lie in a common plane at right angles to the axis of said hub, each plate being in the form of a sector whose center of curvature coincides with the axis of said 15 hub, and having along one of its radial edges

a lip which is bent outward and is sharpened to form a knife or cutter, and the said arms being separated from one another and having their outer ends at a distance from the axis of said hub, so as to leave a clear space between 20 the inner end of the hub and the said sector-shaped plates at the center of the cutter-head, substantially as described.

In testimony whereof I have signed this specification in the presence of two witnesses. 25

HENRY T. CLAWSON.
